UNITED STATES PATENT OFFICE.

JOHN J. ROBERTS, OF READING, PENNSYLVANIA.

ROLLING-MILL.

SPECIFICATION forming part of Letters Patent No. 276,629, dated May 1, 1883.

Application filed December 20, 1882. (No model.)

To all whom it may concern:

Be it known that I, JOHN J. ROBERTS, a citizen of the United States, residing at the city of Reading, county of Berks, and State of Pennsylvania, have invented a new and useful Improvement in Rolling-Mills, of which the following is a specification.

My invention relates more particularly to what is termed the "small" or "merchant" train of a rolling-mill plant; and it consists in such modification of the construction of the rolls therefor as will very materially reduce the cost of the same.

The object of my invention is to improve the product of the mill, increase its output, decrease the capital invested in rolls, and give increased strength to the same, decreasing the liability to accidents in operating the same. I attain these objects by the construction of the rolls in the manner illustrated in the accompanying drawings, in which similar letters refer to similar parts throughout the drawings forming part of this specification—

Figure 1, Sheet 1, representing a front elevation of a complete merchant-bar mill for iron or steel, showing my improved rolls and housings on the left-hand side. Fig. 2, Sheet 1, represents a set of rolls for a three-high mill in accordance with my improvement. Fig. 3, Sheet 1, is an end view of the same. Fig. 4, Sheet 2, represents a set of rolls for square bars, preferably used in connection with my improvement. Fig. 5, Sheet 2, is an end elevation of a housing adapted to my improvement. Fig. 6, Sheet 2, is a front elevation of the same. Fig. 7, Sheet 2, plan, side, and front elevation of rider or bearing-boxes used in the housings. Fig. 8, Sheet 2, represents the adjusting-keys. Fig. 9, Sheet 2, represents the side guides used in combination with the improved rolls.

A represents the housing-shoe, adapted to fit the feet of the housings mounted thereon, and is provided with the usual longitudinal holding-down-bolt recess, A', in which the bolt-heads slide. B represents the housings for the rolls; B', the nut-boss; B², the housing-screw; B³, inclined mortises in the legs for the keys F, and B⁴ housings for the driving-pinions; B⁵, caps, and R⁶ screws for same. C represents the usual fore plate, and D the ordinary side guides used in rolling metal. E

represents the seat for the lower roll, and E' the riders for the middle and top rolls. These are provided with a key-groove, E², corresponding with the mortise B³ in the housing-legs. F are adjusting-keys—one broad and one narrow—passing entirely across the housing-legs in the mortises B³, and are secured in place by set-screws F'. g represents the ordinary three-high roughing-rolls. h represents an ordinary set of three-high square-bar finishing-rolls, and J represents my improved step flat-bar rolls adapted to a three-high mill. K represents a bar of metal passing through the several series of rolls and emerging as a finished flat bar from my improved rolls in one continuous operation. L are the ordinary coupling-boxes; M, the driving-pinions.

It is well known to experts in rolling-mills that rolls for flats, from the manner of their construction, are more liable to breakage and accidents of every description than any others of the set. It is also well known that to manufacture all of the marketable sizes of flat iron usually kept in stock requires a multiplicity of rolls, usually amounting to tons of the same. It is also well known that to form the various sizes it is common to throw the rolls out of horizontal level, and thus put a great strain upon the necks of the rolls and the coupling-boxes uniting the same, the wabbling of which at times creates an overpowering clatter; also, that after wear, the space between the collars and seats becoming enlarged, it is not an unusual occurrence for the bar to catch while passing through, and either split off the collar, spoiling the roll, or winding thereon to break the same.

My system of rolls abolishes all of the above defects of the system now in use. Preferably the roughing and squaring-up rolls are run face to face, with the grooves equally divided between them. Their alignment is therefore direct from the pinions, and my step-rolls having their bearings rigidly adjustable by the keys F, their center horizontal line will agree with the other sets of rolls. The housings are provided with the usual fore and back plates, and upon the fore plates are mounted the usual side guides, so arranged relative to the size of bar desired that the same shall be passed through the step-opening between the rolls adapted to form said size of bar, in this re-

spect not differing from present practice in small mills. In a set of step-rolls constructed in accordance with my improvement, I prefer to have them, for a merchant-mill, twenty-four inches between the necks, ten inches diameter at large end, and eight and one-quarter inches at the small end, necks five and one-half inches diameter and six inches long. On rolls of the above size I have eight risers and nine steps or treads equally divided between the two extreme diameters. The treads or steps vary from three to two and one-half inches in width. My system is, however, applicable to all mills, the only difference being that for shorter rolls there will be fewer steps, and more than one set of rolls will be required.

In operation the billet is first passed through the roughing-rolls, the grooves selected being those fitting it for the desired pass in the squaring-up rolls, and from them to the step-rolls, where it is reduced to a flat bar. This operation may be continuous, as shown in Fig. 1, Sheet 1, in which K represents the billet, entering the roughing-rolls at the right and emerging on the left from the upper step-rolls a finished flat bar.

It will be noticed that I have the coupling-boxes placed directly upon the necks of the rolls, without the intervention of the usual spindle. In this way the mill becomes more compact and better adapted to do good work. If preferred, the spindles may be used with double coupling-boxes, as at present.

I find in practical use, the corners of the bar being filled out in the square-finishing rolls, that in its reduction to a flat bar in the passage through the step-rolls the edge of the bar remains full and square. As usually arranged, I place my step-rolls in the housings at such a distance from center to center as will leave a space of one-fourth of an inch between the faces of the rolls at their largest diameter. This space may be reduced or enlarged by a manipulation of the key F, which raises or lowers and rigidly maintains the positions of the rolls relative to each other as the keys are

driven out or in. In either position the set-screws F' are tightened upon them and they are securely retained, as desired.

Rolls constructed in accordance with my system may be more rapidly finished in the lathe and do not require the same degree of skill to produce as the present flat-bar rolls. The rolls under my system are much stronger for the same diameter than under the present system of collars and recesses in opposite rolls, which often reduces the body of the roll to a less diameter than the necks of the same.

As before remarked, my invention will make a great reduction in the plant required to produce bar-iron. The regular variation in the steps of the rolls, with the facility for increasing or diminishing the space by the keys, as described, gives superior advantages to the manufacturer in the production of odd sizes of bars. The repairs are simple, being confined to a straight surface, and the rolls may be used for many years before they would be thrown to one side for want of strength, whereas under the present system the rolls are soon worn out and rendered unfit by reason of weakness to be further reduced in diameter by re-turning on the lathe.

I am aware that keys for raising and retaining the riders of housing-rolls, as shown in Figs. 5, 6, and 8, are not new; but I give preference to said mode of adjustment as the simplest and most reliable.

Having described my improvement, shown the construction, and recited the advantages of the adoption of the same, I desire to secure by Letters Patent the following claim:

As a new device for the manufacture of merchant-bar in iron or steel, a stepped roll void of collars, constructed as shown and described, adapted to be used in roll-housings in sets of two, three, or more high, substantially as and for the purpose specified.

JOHN J. ROBERTS.
